CANOPY LETTER GRAPPLER

Theodore C. Lotz, Minneapolis, Minn.

Application January 27, 1949, Serial No. 73,205

2 Claims. (Cl. 294—19)

1

This invention relates to an improved canopy letter grapple for removing and placing letters or numbers in a canopy or marquee at motion pictures houses, hotels, night clubs, etc.

It is an object of this invention to provide a canopy letter grapple which will firmly hold a letter or the like so that it may be removed or mounted in a canopy marquee at a theatre or the like.

It is a further object of this invention to provide a canopy letter grapple with a handle means whereby plates in the forms of letters, etc. may be mounted in and removed from a display sign mounted ten or more feet above the street level by a person from the street level.

It is a further object of this invention to provide a letter grapple having means for securely holding relatively large plates or the like when mounting or removing them from marquees, signs or the like.

It is a still further object of this invention to provide a grapple having means for easily actuating jaws of the grapple.

Other and further objects will appear from the detailed description of the grapple and the appended claims.

The invention will be more fully explained hereinafter with reference to the accompanying drawing in which it is illustrated, and in which:

Figure 1 is a side view of the improved grapple, parts in section.

Figure 2 is a sectional view of the connection means between the trigger on the grapple and the actuating means for the jaws taken on line 2—2 of Figure 1.

Figure 3 is a sectional view taken on line 3—3 of Figure 1 disclosing the lower bifurcated jaw.

Figure 4 is a detailed view, partly in elevation and partly in section of the actuating means in depressed position with the lower movable jaw shown in open position with respect to the fixed jaw.

Figure 5 is an elevational view of a portion of a theatre marquee.

Figure 6 is a side view of the improved grapple part in section, holding a plate or metal letter.

Figure 7 is a sectional view of modified means of connecting a handle to the grapple.

Figure 8 is a front view of a portion of a letter showing the outer end of the jaws of the grapple holding the letter.

Figure 9 is a rear view of a portion of a letter disclosing the outer ends of the jaws of the grapple holding the letter.

The drawings are now referred to in detail, 55 movable jaw 14. The plate 58 is adapted to pivot

2

especially Figure 1, the grapple is designated by the numeral 10. The grapple comprises a fixed jaw 12 and a pivoted jaw 14. The fixed jaw is provided with an end 16 slightly bent upwardly from the horizontal portion 18, see Figure 1. A depending support arm 20 is detachably secured by screws to the inside face of the fixed jaw 12 adjacent the inner end of the upstanding portion 16 for a purpose to be set forth hereinafter. The 10 ends of the arm 20 extend beyond the sides of the stationary and fixed jaws 12 and 14 respectively. The inner end of the fixed jaw 18 is provided with an enlarged cylindrical portion 22 having a passage 24 therethrough. The lower 15 or pivoted jaw 14 is provided with a hinge 24 which is fastened at 26 to the fixed jaw 12. A substantially V-shaped notch 28 extending completely across the pivoted jaw 14 adjacent its outer end and substantially opposite the support arm 20 on the fixed jaw 12 so that the arm 20 cooperates with the V-shaped notch 28 for a purpose to be set forth hereinafter. The outer end of the pivoted jaw 14 is bifurcated as at 30.

A trigger 32 is pivotally secured by bolt and 25 nut means 34 to a lug 36 formed integrally with the fixed jaw 12. A demountable pin 38 is mounted in appropriate apertures in the front portion of the trigger 32. An arm 40 is freely mounted on the pin 38 and is provided with an 30 aperture adjacent its rear end for a purpose to be set forth hereinafter. An internally threaded connection 42 is provided with a bifurcated portion at its rear end for freely mounting the connection 42 on the pin 38 associated with the trigger 32. A bolt 44 having a threaded shank carries a nut 46 thereon. The threaded end of the bolt 44 is adjustably associated with the screw threaded aperture in the connection 42. A generally U-shaped element 48 has its legs 50 35 mounted respectively on the opposite ends of a pin 52 carried in an aperture in the top portion of a plunger 54 with the legs 50 abutting the opposite sides of the plunger 54. The legs 50 of the element 48 are held on the pin 52 by cotter pins against the opposite sides of the plunger 54. The fixed jaw 12 is provided with a slot 56 through which the plunger 54 extends. There is a small plate 58 secured to the lower end of the plunger 54 adjacent its front edge which is carried between the fixed jaw 12 and movable jaw 14. The plate 58 is rounded across its rear edge 60. The rounded edge 60 fits into abutting recesses in front plate of hinge 24 and in the front edge of a plate 62 secured between hinge 24 and

on its rounded edge 60 in the recesses in the edge of hinge 24 and plate 62 when plunger 54 is depressed by means of trigger 32.

A plurality of leaf springs 64 are held in operable relationship with the movable jaw 14 by a bolt 66 which extends through a hole in the movable jaw 14 and is secured to the fixed jaw 12.

The end of a handle not shown is insertable in the passage 24 in the enlarged portion 22. The handle is preferably hollow with a wire or the like carried therein. The end of the wire is adapted to be secured to the arm 40. A trigger similar to trigger 32 is pivoted adjacent the outer end of the handle with the outer end of the wire attached to a portion of the trigger. When such a handle is associated with the grapple 10, a person can actuate the grapple from the outer end of the handle.

Figure 6 discloses a canopy letter grapple similar to the grapple 10 of Figure 1 except that it is provided with an enlarged portion 70 associated with the fixed jaw 12. The enlarged portion 70 is provided with a passageway 12 for the passage of a wire 76, and the rear end of the enlarged portion is reduced and screw threaded at 73. A hollow handle 74 has a screw threaded portion so that the handle 74 can be fastened to the reduced portion 73 of the fixed handle 12. A trigger 80 is pivoted adjacent the rear of the handle 74 and the outer end of the wire 76 is secured to the trigger 80.

A portion of a marquee 90 is shown in Figure 5 with a letter 84 representing the letter "W" mounted on spaced wires 92 and 94 of the marquee 90. The letter 84 is provided with hooks 85 by which the letter is mounted on the wires 92 and 94. The grapple of Figure 6 is shown holding the letter 84 between its jaws.

The grapple 10 is used to mount letters and numbers, such as a letter 84 on a marquee or canopy of a theatre and to remove such letters so that the display of the marquee will always indicate what motion picture and the like is being shown in the theatre.

The depressing of trigger 80 actuates wire 76 which pulls back plunger 54 through means of arm 40, connection 42, bolt 44 and U-shaped element 48, see Figures 1, 4 and 6. The plunger 54 pivots plate 58 at its edge 60 which pivots jaw 14 downwardly away from the fixed jaw 12, thus separating the movable jaw 14 from the fixed or stationary jaw 12. When the jaws of the grapple 10 are thus separated, the jaws can grasp a letter 84. The angular portion 16 of the fixed jaw engages the front portion of the letter 84, and the bifurcated portion 30 engages the rear side of the plate with the notched portion 28 in the pivotal jaw 14 receiving the rearwardly extending flange portion 86 at the lower edge of the letter 84. The outer face of the support element 20 abuts the lower edge of the flange 86. The support 20 extends beyond the sides of the stationary jaw 12 and pivotal jaw 14 to provide a support for the lower edge of extra large letters such as an "M." The bifurcated portion 30 on the pivotal jaw 12 permits the outer end of the pivotal jaw 14 to straddle a hook such as 85 which is secured to the rear side of a letter at its lower end. Where there is no hook in the rear side of a letter at its lower end, then the outer end of the pivoted jaw 14 may be solid similar to the outer end of the stationary jaw.

When pressure is released from the trigger 80 or 32, then the leaf springs 64 will move the

pivotal jaw 14 toward the stationary jaw 12 and a plate will be firmly held between the two jaws, until the trigger 80 or 32 releases the jaws so that the plate 84 or the like can be removed from the jaws of the grapple 10.

If it becomes necessary to vary the distance the pivotal jaw 14 moves or pivots away from the stationary jaw 12, then the distance between the U-shaped element 48 and the connector 42 is varied by adjusting the nut 46 and bolt 44 with respect to the connector 42. When it is desirable to permit the pivotal jaw 14 to move farther away from the stationary jaw 12, nut 46 is loosened or screwed away from the end of connector 42 and bolt 44 turned or partially screwed out of the connector 42 thus increasing the distance between the arm 48 and connector 42 and raising trigger 32 farther away from jaw 12. After the bolt 44 has been partially screwed out of the connector 42, the nut 46 is again screwed tightly against the end of the connector 42 to securely hold the bolt 44 in its adjusted position in the connector 42. Thus when the trigger 32 has a greater pivotal movement, the jaw 14 pivots farther from the stationary jaw 12. If it is desirable to decrease the distance, the pivotal jaw 14 moves away from the stationary jaw 12, then the distance between the U-element 48 and the internally threaded connector 42 is decreased by screwing the bolt 44 farther into the connector 42 than the adjustment shown in Figure 1 thus moving trigger 32 closer to the jaw 12 so that trigger 32 will have a smaller pivotal movement.

It is possible to utilize handles of different lengths with the grapple 10 so as to be able to easily remove letters from marquees at motion picture houses which may be at different elevations from the sidewalk.

The present grapple easily and quickly aids in mounting and removing letters from advertising display mounted on elevated boards, marquees, canopies or the like.

Having described my invention and illustrated an embodiment by which the same may be practiced, what I claim is:

1. In a grapple of the class described, a stationary jaw, a support element secured adjacent the outer end of the stationary jaw, a second jaw pivotally mounted on the stationary jaw, a notch extending completely transversely of the pivotal jaw adjacent its outer end, the support element mounted on the stationary jaw opposite the notch in the pivotal jaw, actuating means associated with the pivotal jaw comprising a plunger, a pivotal plate mounted between the stationary and pivotal jaw, the plunger engaging the pivotal plate, a trigger means connected to the plunger operating the pivotal plate for moving the pivotal jaw.

2. In a grapple of the class described, a stationary jaw, a support element secured transversely of the stationary jaw adjacent its outer end with the ends of the support element extending beyond the sides of the stationary jaw, a pivotal jaw associated with the stationary jaw, a notch extending completely across the pivotal jaw adjacent its outer end, the support element mounted on the stationary jaw opposite the notch in the pivotal jaw, actuating means associated with the pivotal jaw comprising a plunger, a pivotal plate mounted between the stationary and pivotal jaws, the plunger engaging the pivotal plate, a trigger, means connecting the trigger with the plunger for actuating the pivotal plate operating the pivotal jaw.

3. In a grapple of the class described, a stationary jaw, a support element secured transversely of the stationary jaw adjacent its outer end with the ends of the support element extending beyond the sides of the stationary jaw, a pivotal jaw associated with the stationary jaw, a notch extending completely across the pivotal jaw adjacent its outer end, the support element mounted on the stationary jaw opposite the notch in the pivotal jaw, actuating means associated with the pivotal jaw comprising a plunger, a pivotal plate mounted between the stationary and pivotal jaws, the plunger engaging the pivotal plate, a trigger, means connecting the trigger with the plunger for actuating the pivotal plate operating the pivotal jaw, and adjustable means

associated with the connecting means for varying the length of the connecting means so that the distance the pivotal jaw moves from the stationary jaw may be varied.
